UNITED STATES PATENT OFFICE.

JOHN D. HALL, OF ORRVILLE, OHIO.

MACHINE FOR FORMING CALKS ON HORSESHOES.

1,054,967.

Specification of Letters Patent.

Patented Mar. 4, 1913.

Application filed October 12, 1912. Serial No. 725,385.

To all whom it may concern:

Be it known that I, JOHN D. HALL, a citizen of the United States, residing at Orrville, in the county of Wayne and State of Ohio, have invented a new and useful Machine for Forming Calks on Horseshoes, of which the following is a specification.

My invention relates to improvements in machines for forming the heel calks upon horseshoes and has for its object, to provide a mechanism by which the heel calks may be formed and finished without reheating the shoe. This object together with other objects readily apparent to those skilled in the art may be attained by the construction illustrated in the accompanying drawings, although the invention may be embodied in other forms, the construction illustrated being chosen by way of example.

Figure 1 is a front elevation of the machine. Fig. 2 is a rear elevation. Fig. 3 is a plan view with the top plate removed and parts broken away. Fig. 4 is a vertical longitudinal section upon the line 4—4, Fig. 3. Fig. 5 is a vertical transverse section on the line 5—5, of Fig. 4. Fig. 6 is an end elevation. Fig. 7 is a perspective view of a portion of a horseshoe showing one of the heel calks completed. Fig. 8 is a longitudinal sectional view of a modified form of my device. Fig. 9 is a top plan view with the upper plate removed and parts broken away, of the modified form. Fig. 10 is a perspective view of a portion of a horseshoe showing one of the shoe calks completed.

Similar numerals of reference indicate corresponding parts in all the figures of the drawings.

1 indicates a suitable support for the machine proper. The upper and lower plates 2 and 3 respectively are spaced apart by means of the corner posts 4, which are connected to said plates by any suitable means such as the bolts 5. The die block 6 and the horseshoe holding block 7 are slidably mounted within the grooves 8 and 9 in the plates 2 and 3 respectively. The die block 6 is provided with the reduced die portion 10 having the shoulders 11 and 12 thereon. At one end of the machine is located a shaft 13 journaled in suitable bearings 14 upon the posts 4 and provided at one end with a pulley 15. The cams 16 and 17 are fixedly mounted upon the shaft 13 and are adapted to bear against the ends of the die block 6 and holding block 7 respectively.

Upon the rear end of the shaft 13 is located a pitman wheel 18 provided with a wrist pin 19 upon which is loosely mounted one end of the pitman rod 20, the opposite end of said rod being connected to the rock arm 21 mounted upon the rock shaft 22, said rock shaft being journaled in suitable bearings 23 located upon the lower plate 3. Intermediate said bearings is located a rock arm 24, to which is pivotally connected the arm 25 of the die 26, said die being provided with a plunger 27 adapted to reciprocate within the cylindrical opening 28 located in the die block 6.

Journalled in suitable bearings 29 upon the upper plate 2 is a rock shaft 30 provided upon its rear end with a rock arm 31 to the end of which is attached one end of the pitman rod 32, the opposite end of said pitman rod being attached to the wrist pin 19 upon the pitman wheel 18. Intermediate said bearings 29 is located a cam 33 upon the shaft 30, said cam being adapted to bear upon the upper face of a plunger 34, said plunger being provided with an arm 35 journaled at 36 to a block 37 located upon the plate 2. A spring 38 located in a socket 39 in the plate 2 is adapted to bear against the lower face of the arm 35 and normally hold the plunger 34 in contact with the cam 33. A similar rock shaft 40 is journaled in suitable bearings 41 upon the lower plate 3, said rock shaft being provided upon its rear end with a rock arm 42, to the end of which is attached one end of the pitman rod 43, the opposite end of said pitman rod being attached to the wrist pin 19 upon the pitman wheel 18. Intermediate said bearings 41 is located a cam 43, said cam being adapted to bear upon the lower face of the plunger 44, said plunger being provided with an arm 45 journaled at 46 to a block 47 located upon the plate 3. A spring 48 located in a socket 49 in the plate 3 is adapted to bear against the lower face of the arm 45 and normally hold the plunger 44 in contact with the cam 43.

A gage block 50 is slidably mounted in the transverse grooves 51 and 52 in the upper and lower plates 2 and 3, respectively. Guide pins 53 are provided upon said block. A vertical bar 54 is located in front of the block 50 and is supported by the plates 2 and 3 in any suitable manner such as the screws 55. Set screws 56 are carried by said bar and adapted to bear

against the forward face of the block 50 for adjusting the same.

A suitable weight 57 is suspended by means of a cord 58, the ends of which pass over the shaft 13 and are secured to the die block 6 and holding block 7 as at 59 and 60 respectively.

The operation of the device is as follows: The heels of the horseshoe as shown in dotted lines at 61 in Figs. 1, 3 and 4, are placed between the guide pins 53 so as to bring them upon either side of the reduced portion 62 of the die 26, their ends striking the face 63 of the die 10. Then as the shaft 13 is rotated the cam 16 will move the die block 6 to the right, the shoulder 12 upon said die block striking the heel of the horseshoe and bending it at right angles upon the inner face 64 of the gage block 50. At the same time the shaft 22 will be rocked by means of the pitman 20 drawing the die 26 toward the die block 6, the shoulder 65 upon the die 26 coming in contact with the turned-over end 66 of the horseshoe heel. The shoulder 11 will then be brought into contact with the face 67 of the horseshoe heel and at the same time the cam 17 will move the holding block 7 forward until it comes in contact with the horseshoe, thereby holding it firmly in place during the rest of the operation. During this operation the cams 33 and 43 will be brought to bear upon the plungers 34 and 44 respectively, thereby squaring up the side faces 68 and 69 of the horseshoe heels between said plungers and the faces 70 upon the die 26. A still further rotation permits said plungers 34 and 44 to be withdrawn and the weight 57 pulls the die blocks 6 and holding blocks 7 back to the normal position when the horseshoe may be removed and another one inserted for the next operation. It will be noticed that only one revolution is necessary to complete the operation.

By adjusting the gage block 50 it will be seen that the heel calk will be made thicker or thinner as desired.

For the purpose of forming a sharp calk upon the heels for use upon icy pavements I have provided a modification of my device whereby such calks may be formed. In the modified form the reduced portion 10^a upon the die block 6^a is provided with a pair of rollers 71 journaled at their lower extremities in suitable apertures in the reduced portion 10^a, their upper ends being journaled in slots such as 72, and held in place by any suitable means as the caps 73. Referring to Figs. 8 and 9 of the drawings it will be seen that the rollers 71 are flush with the face of the reduced portion 10^a of the die block. A die 26^a is used in this form of invention, said die having upper and lower faces 70^a. The gage block 50^a

used in this form of the device is provided with extensions such as 74, which project between the faces 70^a of the die 26^a and the plungers 34 and 44. These extensions are provided with beveled faces such as shown at 75.

The operation of the modified form of the device is practically the same as in the first form. Each roller 71 will pass across the face 76 of the calk, forcing said calk between said roller and the beveled face 75 of the gage block 50^a, thereby, forming the beveled face 77 upon the calk. The plungers 34 and 44 will operate in the same manner as in the other form of the device, compressing said calk between said plungers and the faces 70^a of the die. 75 80 85 90

I claim—

1. In a machine of the character described, a die block, a cam adapted to reciprocate said die block, a die adapted to move toward said die block, a rock arm adapted to reciprocate said die, a gage block, guide pins upon said gage block, a holding block adapted to move toward said gage block, a cam adapted to reciprocate said holding block, means for holding said die block and holding block in contact with said cams, upper and lower plungers adapted to move toward said die, cams adapted to move said plungers, means for holding said plungers in contact with said cams and means for operating said cams and said rock arm. 95

2. In a machine of the character described, upper and lower plates provided with longitudinal grooves, posts connecting said plates, a die block mounted for reciprocation within said grooves, a cam adapted to reciprocate said die block, a holding block mounted for reciprocation within said grooves, a cam adapted to reciprocate said holding block, means for holding said die block and holding block in contact with said cams, a gage block carried between said upper and lower plates, guide pins upon said gage block, said die block provided with a cylindrical opening, a plunger adapted to reciprocate within said opening, a die carried by said plunger, a rock arm adapted to reciprocate said die, upper and lower plungers mounted upon said plates, cams adapted to move said plungers toward said die, means for holding said plungers in contact with said cams and means for operating said cams and said rock arm. 100 105 110 115 120

3. In a machine of the character described, upper and lower plates provided with longitudinal grooves, a die block mounted for reciprocation within said grooves, a holding block mounted for reciprocation within said grooves, a shaft mounted at one end of said machine, cams carried by said shaft adapted to reciprocate said die block and said holding block, means for holding said holding block in contact with said cams, a die adapted to 125 130

be reciprocated toward said die block, a rock shaft located upon said lower plate adjacent said die, a rock arm carried by said rock shaft and connected to said die, a second 5 rock arm carried upon the end of said rock shaft, a pitman wheel carried by said shaft, a pitman rod connecting said pitman wheel to said second mentioned rock arm, upper and lower plungers pivotally mounted upon 10 said upper and lower plates respectively, upper and lower rock shafts mounted above and below said upper and lower plungers respectively, cams carried by said rock shafts, adapted to engage said plungers, 15 rock arms carried upon said upper and lower rock shafts, pitman rods connecting said rock arms to said pitman wheel, means for holding said plungers in contact with said cams, a gage block located adjacent said die 20 between said upper and lower plates, guide pins carried by said gage block, means for adjusting said gage block and means for rotating said shaft.

4. In a machine of the character described, 25 a die block, means for reciprocating said die block, a die adapted to be reciprocated to-

ward said die block, means for reciprocating said die, a gage block located adjacent said die, a holding block adapted to be reciprocated toward said gage block, means 30 for reciprocating said holding block, upper and lower plungers, and means for moving said plungers toward said die.

5. In a machine of the character described, 35 a die block, rollers carried by said die block, means for reciprocating said die block, a die adapted to be reciprocated toward said die block, means for reciprocating said die, a gage block located adjacent said die, a holding block adapted to be reciprocated toward 40 said gage block, means for reciprocating said holding block, upper and lower plungers and means for moving said plungers toward said die.

In testimony that I claim the above, I 45 have hereunto subscribed my name in the presence of two witnesses.

JOHN D. HALL.
